UNITED STATES PATENT OFFICE.

HENRY H. HUNT, OF JERSEY CITY, NEW JERSEY, ASSIGNOR TO THE HARTFORD CARPET CORPORATION, A CORPORATION OF CONNECTICUT.

DESIGN FOR CARPET.

SPECIFICATION forming part of Design No. 37,106, dated August 30, 1904.

Application filed May 14, 1904. Serial No. 208,046. Term of patent 3½ years.

To all whom it may concern:

Be it known that I, HENRY H. HUNT, a citizen of the United States, and a resident of Greenville, Jersey City, in the county of Hudson and State of New Jersey, have invented a new, original, and ornamental Design for Carpet, of which the following is a specification.

The figure of my new and original design, as shown in the accompanying drawing, illustrates a section of a carpet having said design thereon.

The drawing shows two of the large figures complete, while the lower and upper portions of one of the other figures are shown at the top and bottom, respectively, of the drawing, and the right and left portions of the remaining large figures are shown at the left and right side, respectively, of the drawing.

What I claim as new, and desire to secure by Letters Patent, is—

The ornamental design for a carpet substantially as shown.

HENRY H. HUNT.
